(57) **CLAIM**

The ornamental design for a diaper with bond pattern, as shown and described.

DESCRIPTION

FIG. 1 is a perspective view of a diaper with bond pattern showing our new design;

FIG. 2 is a front view of the diaper with bond pattern as shown in FIG. 1;

FIG. 3 is a back view of the diaper with bond pattern as shown in FIG. 1;

FIG. 4 is a left side view of the diaper with bond pattern as shown in FIG. 1;

FIG. 5 is a right side view of the diaper with bond pattern as shown in FIG. 1;

FIG. 6 is a top view of the diaper with bond pattern as shown in FIG. 1;

FIG. 7 is a bottom view of the diaper with bond pattern as shown in FIG. 1;

FIG. 8 is a perspective view of a diaper with bond pattern showing our new design;

FIG. 9 is a front view of the diaper with bond pattern as shown in FIG. 8;

FIG. 10 is a back view of the diaper with bond pattern as shown in FIG. 8;

FIG. 11 is a left side view of the diaper with bond pattern as shown in FIG. 8;

FIG. 12 is a right side view of the diaper with bond pattern as shown in FIG. 8;

FIG. 13 is a top view of the diaper with bond pattern as shown in FIG. 8;

FIG. 14 is a bottom view of the diaper with bond pattern as shown in FIG. 8;

FIG. 15 is an enlarged view of a portion of the diaper shown in FIG. 2, at lower left; and,

FIG. 16 is an enlarged view of a portion of the diaper shown in FIG. 9, at lower left.

(Continued)

The broken lines shown in FIGS. 1-16 illustrate portions of the diaper with bond pattern and form no part of the claimed design.
